UNITED STATES PATENT OFFICE.

BENJAMIN F. DALY, OF NEW YORK, N. Y.

POST AND BOX FOR CABLE-TERMINALS AND THE LIKE.

No. 831,327.

Specification of Letters Patent.

Patented Sept. 18, 1906.

Application filed December 15, 1905. Serial No. 291,882.

To all whom it may concern:

Be it known that I, BENJAMIN F. DALY, a citizen of the United States, residing in the borough of Brooklyn, in the county of Kings, in the city and State of New York, have invented certain new and useful Improvements in Posts and Boxes for Cable-Terminals and the Like, of which the following is a specification.

10 In some localities, and particularly in cities, a metal post is employed for gas-lamps, for signal-boxes, such as those for electric fire-alarm signals, and for receptacles for electric cable-terminals, and it is to this class of devices that the present invention relates. The invention relates to the general structure of the sectional post, capable of being used for all these purposes, and particularly to the member or portion which provides the box to receive the cable-terminals.

The invention will be fully described hereinafter with reference to the accompanying drawings and the novel features carefully defined in the claims.

25 In the said drawings, Figure 1 is an elevation of the sectional post on a relatively small scale. Fig. 2 is an axial section, on a larger scale, of the upper member of the post; and Fig. 2^a an upper end view of said member, showing the square tenon. Fig. 3 is an enlarged axial sectional view of the middle member of the post. Fig. 4 is a longitudinal axial sectional view of the lower and middle members of the post, taken in the plane indicated by line x⁴ in Fig. 6. Fig. 5 is an axial section of the lower member of the post, the plane of the section being at right angles to that of Fig. 4. Fig. 6 is a transverse section on a still larger scale, the plane of the section 30 being indicated by line x⁶ in Fig. 5. Fig. 7 is an under side view of the bottom of the post, the hexagonal base-piece being in section at line x⁷ in Fig. 1. Figs. 8, 9, and 10 illustrate the preferred means for conducting the cables from the ground-conduits to the cable-terminals in the post. Figs. 8 and 9 are respectively vertical sections of the base or stump, taken at lines x⁸ and x⁹ in Fig. 10, and the latter figure is a plan view of the base.

45 Referring especially to Fig. 1, A is the base of the post, which is set in the ground. B is the lower or first member of the post. This member is in substance a hollow casing which contains the box or receptacle to receive the cable-terminals. C is the second or middle member, adapted to receive the signal-box,

and D is the third or upper member to receive the lamp E. Figs. 2 and 3 (show in longitudinal section) the members D and C detached. The lower member B is bolted to the base 60 and has at its top a socket a, which receives a tubular tenon b on the member C, Fig. 4, and the member C has at its top a similar socket c to receive a tubular tenon d, Fig. 2, on the bottom of the member D. At its top the 65 member D, which is the lamp-support, has a square tenon e, (seen also in Fig. 1,) where the socket is broken away. The lamp E has a socket f to receive the tenon e. In Fig. 1 F designates a signal-box set in the recess X, 70 formed in the section C to receive the box, Fig. 3.

In case the post is only designed for the time to provide a box for the cable-terminals and the upper members are omitted the opening at the top of the member B may be closed, Fig. 5, by a stopper g, fitting in the socket a, or if only the lamp and lamp-supporting member D are to be for the time omitted, Fig. 4, a similar stopper h may be 80 fitted in the socket b of the member C. These stoppers serve to close the hollow post at its top to prevent water from getting in and to give a finish to the structure.

It will be noted that the post is hollow 85 from the ground up to the lamp, and the latter may be supplied with gas from a pipe extending up through the post in the usual way. The pipe is not herein shown.

The construction of the member B will 90 now be described in detail with especial reference to Figs. 4, 5, and 6. This member or casing has in its opposite faces doors i i to afford access to the terminal box G, which also has in its opposite faces doors j j, opposite, respectively, to the doors i i and affording access to the box G when either of the doors i is opened. The box G is secured to the walls of the casing by means of screws k, and the doors j thereof are secured to the 95 box at their lower ends by means of hooks m and at their upper ends by hasps and locks n. By unlocking the door j at its upper end it may be disengaged from the box G and lifted out. Within the box is a plate o, of slate or the like, fixed in an upright position by screws p and provided with holes r to receive binding-posts for making the wire connections in a known way. This plate faces the doors. At its bottom the box G has two 105 large conduit-pipes s s, which extend down into the hollow base, and up through these 110

are brought the cables, the wires from the cables being connected to the respective binding-posts on the plate *o*.

An important advantage of this construction of the member *B* of the post and the internal features is that it affords ready access to both sides of the plate *o* for inspection and for making the desired connections with the wires of the cables. The signal-box *G* may be connected with any wires of the cable that may be desired.

The base or stump *A* (shown in Fig. 1) is substantially the same as that ordinarily employed with this class of posts; but the preferred base is illustrated in Figs. 8, 9, and 10. In this construction the hollow hexagonal base *A'* has in each of its sides, by preference, an aperture *t* and in its top a recess to receive the circular flange *u* at the upper end 20 of a trunk-conduit *H* within the hollow of the base. This conduit *H* receives at its top the pipe-conduits *s* from the terminal box *G*, and at its lower end it is curved so as to receive the horizontally-disposed ground-conduits *v*, 25 which enter the base through one or the other of the apertures *t*. Obviously the trunk-conduit may be turned in setting up the post so as to receive the ground-conduits entering at any one of the apertures in the base.

30 The trunk-conduit will be made, by preference, of cast-iron, and it will protect the cables perfectly. The pipe-conduits *s* and *v* may be screwed into the trunk-conduit *H*.

Having thus described my invention, I 35 claim—

1. A device for the purpose specified, comprising a hollow base, a hollow casing secured on said base and provided with a door for access to its interior, and a terminal box for an 40 electric cable mounted in said casing, said box having a door accessible through the door in the casing, pendent conduits for the cable, and a plate with apertures to receive binding-posts for connecting the conductors 45 of the cable.

2. A device for the purpose specified, comprising a hollow base, a hollow casing secured on said base and having in two of its opposite walls, doors which face each other, a terminal-box secured in the casing, said box having also doors in two of its opposite walls,

said doors being disposed opposite to the respective doors in the casing, cable-conduits secured to the bottom of said box, and a plate for wire connections secured in an upright position in the said box and having its two faces presented toward the respective doors of the box, for the purpose specified. 55

3. A device for the purpose specified, comprising a hollow base to set in the ground, a casing member mounted on said base, said member having doors in two of its opposite sides and an opening at *a* in its top, means for closing said opening, and a terminal-box with doors mounted in the casing and provided with means for connecting the terminal wires of the cable. 6c

4. A post for the purpose specified, comprising a hollow base to set in the ground, a hollow casing member *B*, mounted on said base and provided with doors *i* and a socket-opening *a* at its top, and the member *C*, having a tubular tenon *b* to engage the socket *a*, and a recess *X* to receive a signal-box. 7c

5. A post for the purpose specified, comprising a hollow base to set in the ground, a casing member *B*, mounted on the base and provided with doors *i* at its sides and a socket-opening *a* at its top, a member *C*, having a recess for a signal-box, a tubular tenon *b* which fits in the socket *a*, and a socket-opening *c* in its top, a tubular lamp-supporting member *D*, having a tubular tenon *d* which fits in the socket *c*, and a square tenon *e* at its upper end, and a lamp having a socket which 85 fits on said square tenon. 80

6. A post for the purpose specified, having a hollow base provided with an aperture *t* in its side and a recess in its top, a curved trunk-conduit *H* with a flanged top engaging the 90 recess in the top of the base, the conduits *s* connecting with the upper end of said conduit *H*, and the ground-conduits *v* connecting with the lower end thereof.

In witness whereof I have hereunto signed 95 my name, this 14th day of December, 1905, in the presence of two subscribing witnesses.

BENJAMIN F. DALY.
